UNITED STATES PATENT OFFICE.

CARL KÖNIG, OF VOHWINKEL, GERMANY.

CONTROLLING DEVICE FOR RAILWAY-VEHICLES.

1,109,534.

Specification of Letters Patent.

Patented Sept. 1, 1914.

Application filed August 1, 1912. Serial No. 712,655.

To all whom it may concern:

Be it known that I, CARL KÖNIG, engineer, a subject of the Emperor of Germany, residing in Vohwinkel, Germany, have invented certain new and useful Improvements in Controlling Devices for Railway-Vehicles, of which the following is a specification.

The invention consists in a system of control for railway trains and such like, by which it is possible to exactly and continuously ascertain the movements and the position of a vehicle over a prescribed distance from one or more points.

The essential feature of the invention consists in connecting the control conductors along the line to the rails and the train with means of the "Wheatstone bridge" principle, in such a manner that the moving train is the movable contact between the variable resistances, both of the outer ends of the balanced resistances connected with their contact point to the return conductor of the movable contact being connected with each other across signaling devices.

In the accompanying drawings the invention is illustrated in Figure 1 by scheme and in Figs. 2 to 4 in various types.

Referring now to Fig. 1 it is known that the deflection of a galvanometer 1 changes if the contact 2 connected to the generator 6 is moved along the conductor 3—4, that is if the resistance 2—3—5 and 2—4—5 be varied. The reading of the galvanometer is therefore a measure for the distance of the contact 2 from the points 3 and 4. This fact is, according to the invention, made use of for showing the position, direction of movement and speed of vehicles.

In Fig. 2, 7—8 represents a railway line on which travels a vehicle 12. Parallel to the line is stretched a conductor 9—10, corresponding to the line 3—4 in Fig. 1. The branch lines 9—11 and 10—11 correspond to the branches 3—5 and 4—5 in Fig. 1. Point 11 is connected through the rails and wheels of the vehicles to one pole of the generator 13, the other pole of which terminates in a contact 14 which corresponds to point 2 of Fig. 1 and represents the movable contact of the bridge branch 9—10 along which it moves together with the vehicle.

In considering the following diagrams it must be assumed, as it most generally is in practice, that the resistance of the railway conductor 7—8 in Fig. 2, 17—18 Fig. 3 and

38 in Fig. 4, where the same is in parallel with the current conductor, is so small as to be negligible. In order to be able to watch the movement of the vehicle at both ends of the line two signaling mechanism 15 and 16 (galvanometer) are connected in series between the points 9—10.

A second type is the following: 17—18, 19—21—22—20 in Fig. 3 represent the track of a two railed railway in which the rails are insulated from one another. To watch the movement of a vehicle passing over the section 21—22 insulating pieces are inserted at the points 21—22 preventing the passage of current to points 19 and 20. Herein the section 21—22 corresponds to the branch 3—4 in Fig. 1, while the corresponding branches 3—5 and 4—5 are represented by a conductor 21—23—22 laid parallel to 21—22. The point 23 is connected to one pole of the generator 24 the other pole of which is joined to the rail 17—18. The connections of the signaling instruments is the same as in Fig. 2. A vehicle 27, entering the section 21—22 closes the circuit 24 and 23 through its wheels, and the indicators 25 and 26 show the movement of the train.

A third mode of execution for electrically propelled trains is as follows: In Fig. 4 let 28—29 represent the contact line of a single track electric railway lying between two switch points. In order to be able to watch the movements of a vehicle over this line a branch of the bridge circuit 30—31, corresponding to 3—4 in Fig. 1, is arranged parallel to the conductor line 30—32 and 31—32 correspond to 3—5 and 4—5 of Fig. 1. Point 32 connected to the rails corresponds to point 5 and the indicators 33 and 34 to the galvanometer 1 (Fig. 1). How-

ever two signaling devices again are required in order to make it possible to control or watch the vehicles from both ends of the line. The generator 37 is, in this case, replaced by the generators in the central station, one pole of which is connected to the contact line while the other is connected to rails 38. In this case the movable contact (point 2 in Fig. 1) is represented by the trolley 35 of the vehicle which is entering the section 30—31 makes simultaneously contact with the contact wire 28—29 and the bridge branch 30—31 and therefore operates the indicators 33—34. By a resistance 36 inserted between an intermediate point 32 and the rails, the current in

the bridge circuit can be maintained at a predetermined value. With regard to the indicators it may be mentioned that these can be arranged to suit the conditions required. As a general rule it will be sufficient if they show the position and direction of travel of the vehicle. In such cases a galvanometer with a scale corresponding to the length of the section to be controlled, 10 can be used. The direction of movement can be shown by arrows on the scale.

From the foregoing it will be seen that the invention is primarily for the purpose of improving the signaling system and increasing 15 the safety of railways. The form of execution described will however be sufficient to show to an expert the applicability of the controlling system to towing devices, cranes, parcel dispatching plants, rope railways, 20 etc., in short for every kind of transporting system.

What I claim is:

1. In an electrical controlling system for railway trains, in combination, a rail track 25 having practically no electric resistance, two resistance conductors stretched out along the line, and a signaling conductor, the rail track being connected to the middle point of the one resistance conductor, the ends of which 30 are connected, in parallel, to the signaling conductor and to the ends of the second resistance conductor, the said second resistance conductor being connected by the moving train to the rail track, a current source being 35 included in the said connection.

2. In an electrical controlling system for railway trains, in combination, a rail track having practically no electric resistance, two resistance conductors stretched out along the 40 line, and a signaling conductor, the rail track being connected to the middle point of the one resistance conductor, the ends of the two resistance conductors and signaling conductor being connected in parallel, the second 45 resistance conductor being connected by the moving train to the rail track, and a current source being included in the resulting circuit.

3. In an electrical controlling system for railway trains, in combination, a railway train, an electrical connection, two resistance conductors stretched out along the electrical connection, and an indicating conductor, the ends of the resistance conductors being connected in parallel with the indicating conductor, the electrical connection being connected to the middle point of the one resistance conductor, the moving railway train establishing connection between the second resistance conductor and the electrical connection, and a current source being included in the resulting circuit.

4. In an electrical controlling system for railway trains in combination, a moving train, an electrical connection having practically no electrical resistance, two resistance conductors stretched out along the electrical connection, and a signaling conductor, the ends of the resistance conductors being connected in parallel to the signaling conductor, the electrical connection being connected to the middle point of the one resistance conductor, the moving train establishing electrical connection between the second resistance conductor and the said electrical connection, and a current source being included in the resulting circuit.

5. In an electrical controlling system for railway trains in combination, a railway train, an electric circuit established by said railway train, an electric indicator to indicate the direction and the change of volume of the current through said circuit, the change of the current being caused by the travel of said railway train by means of which the position of the train over a prescribed distance may be exactly and continuously ascertained.

In witness whereof I have hereunto signed my name this 23rd day of July 1912 in the presence of two subscribing witnesses.

CARL KÖNIG. [L.S.]
